UNITED STATES PATENT OFFICE

2,624,977

CORD IMPELLED ROTATABLE DISK TOY

Douglas A. Baker, Ottawa, Ontario, Canada

Application March 11, 1950, Serial No. 149,114

1 Claim. (Cl. 46—206)

1

This invention relates to improvements in a toy and appertains particularly to a cord-impelled disk or rotor that I call a racing wheel.

An object of the invention is to provide a rotatable disk-like member that may be easily spun at a high velocity and dropped to the ground to race away on its circumferential periphery.

A further object of the invention is to provide a toy racing wheel rotatable on and slidably off a handle-carried shaft.

A further object of the invention is to provide a rotatable disk having a novel hub structure providing evenly balanced winding drums on opposite sides and an axial bore therethrough to accommodate a withdrawable axle shaft insertable from either side.

A still further object of the invention is the provision of a racing wheel toy of the nature and for the purpose described, characterized by structural simplicity, durability and low cost of production and capable of affording children endless pleasure and interest and an opportunity to develop skill and manual dexterity in its operation.

To the accomplishment of these and related objects as shall become apparent as the description proceeds, the invention resides in the construction, combination and arrangement of parts as shall be hereinafter more fully described, illustrated in the accompanying drawings, and pointed out in the claim hereunto appended.

The invention will be best understood and can be more clearly described when reference is had to the drawings forming a part of this disclosure wherein like characters indicate like parts throughout the several views.

In the drawings:

Figure 1 is a perspective view of the assembled toy, with an impelling cord wound thereon;

Figure 2 is a front elevation of the racing wheel and removable handle;

Figure 3 is a side elevation of the racing wheel alone; and

Figure 4 is an enlarged sectional detail of the hub assembly as taken on line 4—4 of Figure 3, looking in the direction indicated by the arrows.

In the present embodiment of the invention, the racing wheel is seen to comprise a relatively thin stiff disk 1 of cardboard, synthetic plastic or the like that is intended to run along the

ground on its circumferential periphery 2, here shown as having an irregularity in the form of a hump or cam 3. This peripheral irregularity will cause the wheel to leap or jump in its travel and may be dispensed with if desired as a true disk can be made to travel farther.

Centrally the disk 1 is provided with a hub 4, that extends laterally from both sides thereof in the form of a spool or drum with a coaxial bore 5 extending therethrough. This hub is actually formed of a pair of drum parts 4^a and 4^b, the former having a trunnion 4^c on one end that extends through a perforation 6 in the centre of the disk and receives the companion annular drum part 4^b on the projecting length of the trunnion; the disk 1 and the hub parts 4^a and 4^b being securely united in an assembly as shown clearly in transverse section in Figure 4.

The handle consists of a length of rod 7 that may be readily grasped in one hand and includes a pin 8 of reduced diameter continuing from one end and of a size to fit easily in the bore 5 in the wheel hub 4.

In use, an impelling cord 9 is wound on either side of the hub 4 and in either direction and with the hub mounted on the handle pin 8, and with the handle held substantially horizontal or the pintle-like axle shaft slightly elevated, the cord is given a quick pull causing the wheel to spin rapidly on the axle shaft of the handle when the fast revolving wheel is forced longitudinally off the pin 8 by a flip of the finger and the freed wheel races in leaping fashion along the ground.

From the foregoing description taken in connection with the accompanying drawings, it will be manifest that a toy is provided that will fulfill all the necessary requirements of such a device, but as many changes could be made in the above description and many apparently widely different embodiments of the invention may be constructed within the scope of the appended claim, without departing from the spirit or scope thereof, it is intended that all matters contained in the said accompanying specification and drawings shall be interpreted as illustrative and not in a limitative or restrictive sense.

Having thus described the invention, what is claimed as new is:

A freely running, rotatable and freely leaping

toy comprising a hub and a disk having a peripheral protrusion seated on said hub, said hub having an enlarged shoulder portion on one side of the disk and a reduced trunnion portion on the other side thereof, said disk being seated on said trunnion portion against the shoulder portion; a supplemental hub portion coextensive in external diameter and length with the enlarged shoulder portion, said supplemental hub portion being seated on said trunnion portion to secure said disk on said hub and balance same on each side of said disk; an impelling cord windable about said hub on either side of said disk; an axial bore extending through said hub; a handled shaft insertable into said bore from either end to support said toy while it is being rotated, said disk running and leaping freely on its periphery

when released from said shaft after having been started running by said cord.
